[57] CLAIM

The ornamental design for a bean bag game target, as shown and described.

DESCRIPTION

FIG. 1 is a front perspective view of a bean bag game target showing our new design of the present invention;
FIG. 2 is a slightly reduced top plan view thereof;
FIG. 3 is a front elevational view thereof;
FIG. 4 is a back elevational view thereof;
FIG. 5 is a bottom plan view thereof;
FIG. 6 is a left side view thereof, taken from the left side of the figure illustrated in FIG. 3; and,
FIG. 7 is an opposite side view thereof; taken from the right side of FIG. 3.
